CLAIM

The ornamental design for a weighing module, as shown and described.

DESCRIPTION

FIG. 1 is a front perspective view of the weighing module;
FIG. 2 is a front elevation view thereof;
FIG. 3 is a rear elevation view thereof;
FIG. 4 is a left-side elevation view thereof;
FIG. 5 is a right side elevation view thereof;
FIG. 6 is a top plan view thereof; and,
FIG. 7 is a bottom plan view thereof.

The broken lines depict environmental subject matter, are for illustration only and form no part of the claimed design.
